UNITED STATES PATENT OFFICE.

CHARLES H. CURRIER, OF CHICAGO, ILLINOIS, ASSIGNOR TO DRYING SYSTEMS, INC., OF CHICAGO, ILLINOIS, A CORPORATION OF ILLINOIS.

DRYING MEANS.

Application filed February 2, 1920. Serial No. 355,673.

To all whom it may concern:

Be it known that I, CHARLES H. CURRIER, a citizen of the United States of America, and a resident of Chicago, county of Cook, 5 and State of Illinois, have invented certain new and useful Improvements in Drying Means, of which the following is a specification.

This invention relates to methods and 10 means adapted for use in drying siccative coatings, as for instance, in drying-room installations for finishing automobile bodies, furniture, cabinets, and the like, for which purpose it is desirable to treat the air to be 15 used respecting its temperature, humidity, and purity.

Heretofore, attempering or conditioning devices have been installed for washing, humidifying and adjusting the temperature of 20 the air in drying rooms for paint, varnish, and the like, for instance as set forth in my Patent No. 1,230,282, dated June 19, 1917, and separate drying rooms have been provided having different atmospheric conditions 25 corresponding with the several stages generally recognized in the drying process, namely the solvent evaporating stage, the oil oxidizing stage, and the hard drying stage.

The main objects of this invention are to 30 provide an improved process and corresponding means for drying siccative coatings, particularly finishing coats of varnish; to provide successive stages in a continuous drying process whereby the object to be 35 treated may be advanced from one stage to another, in which the atmospheric conditions respecting temperature and relative humidity correspond with the degree of dryness and hardness of the coating; to provide such 40 a system adapted for operation and use all in one room and including a common attempering unit; to provide for improved distribution of the air including cross circulation, and to provide for a final cooling treatment 45 with correspondingly attempered air before discharge from the drying room; to provide in a pluristage drying room means of improved form for circulating the air and distributing same effectually to accomplish 50 the purpose stated; to provide distributed step-by-step attempering means adapted to effect the desired result; to provide for advancing a number of lines of units

to be dried directly from the point of applying the coatings into and through the drying 55 room in parallel relation to and independent of one another; and to provide automatic means for maintaining the desired conditions at a predetermined graded standard throughout. 60

An illustrative embodiment of this invention is shown in the accompanying drawings, in which—

Fig. 1 is a plan of an installation including the essential features of the invention, the 65 view being on a horizontal section at 1—1 of Fig. 2, and the roof of the drying room being removed.

Fig. 2 is a vertical section at 2—2 on Figs. 1 and 3, with the front end wall and doors 70 of the drying room removed.

Fig. 3 is an enlarged vertical section at 3—3 on Fig. 1.

Fig. 4 is a vertical section at 4—4 on Fig. 1, also enlarged.

Fig. 5 is a sectional view of an upwardly turned air supply nozzle equipped with a damper.

Fig. 6 is another form of such a nozzle and damper.

Fig. 7 is a conventional diagram of a consolidated embodiment of the invention.

Fig. 8 is a diagram of conventional character showing the atmospherically responsive fluid pressure motor or diaphragm 85 valve system for automatic attempering control.

In the construction shown in the drawings, the pluristage drying room 1 is built into a larger building or workroom 2 with provision adjacent to the ends of the drying room for installation of the attempering apparatuses 3, such as illustrated at the right end of Fig. 1.

The device 3 here shown includes air washing, heating and humidifying means, namely, the preheater 4, the air spraying washer and humidifier 5, and the reheat 6. Adjacent thereto are flow-pans 7, drip-pans 8, and means for distributing the objects to be 100 coated for parallel entry into the drying room, namely, a transverse runway or distributing space 9.

The drying room as a whole is relatively long and narrow with a number of parallel 105 runways or tracks 10 extending lengthwise

thereof for simultaneous transmission of several lines of the coated objects 11 through the drying room. As here shown there are ten ways which may be regarded as constituting groups A and B of five ways each for the two pans 7 respectively.

A pair of air conduits 12 and 13 extend lengthwise of the drying room, except adjacent to the discharge end, where the cooling apparatus is installed, as hereinafter explained. Said conduits are preferably just above the drying room, one for supplying the treated air, and the other for collecting the vitiated drying-room air and returning same to the initial attempering apparatus or for discharge to a greater or less extent into the open air, as provided for at ventilator 14 at the outlet end of the collecting main 13. The conduit 12 which supplies the treated air for the main body of the drying room is disposed in the upper part of the workroom 2, preferably over the center of the drying room and close to the roof 1' thereof. It comprises a plurality of sections or stages, for example 15, 16, and 17, corresponding with the several progressive temperatures desired, with auxiliary heating means or boosters 18 at the junction points where successive stages meet. These temperature boosters 18 include steam coils or the like, substantially as used in the heaters 4 and 6, as will be understood, though not shown in detail. The relative humidity is decreased by said boosters as the temperature is raised. Each stage is provided with a set of branch discharge conduits 19 extending crosswise of the room in opposite directions, and each having one or more arms 19' extending downward through ceiling 1' and adjacent to the floor, where upwardly turned discharge nozzles 20 are provided adapted to direct the treated air diagonally upwardly and backward crosswise against the coated objects 11, and toward the return conduit 13. Said supply conduit is diminished in size as at the points 21 between successive branching points, so as to compensate for the diminishing air load and thus assure and maintain a uniform pressure for the discharge nozzles 20 throughout the length of the conduit. The branches 19 are all of substantially the same size and character, except that the branches having more than one downward arm are somewhat larger than the others, and are reduced at the arm branching points, as at 19''. Part of the arms 19' are largely hidden behind the pillars 2' which support the roof 2''. Heat is so applied to the attempered air that a relatively slight rise in temperature is provided for the first stage; a somewhat higher temperature is provided for the second stage; and so on, except that in the last stage the temperature is much lower, being preferably about the same as in the first

stage. In this instance the fourth stage is the last or cooling stage, which may be called the tempering stage.

It is to be understood, however, that the number of steps or stages may be varied in designing a plant to suit the particular requirements in any specific case, and that the several stages may in effect merge more or less where they meet.

The air-collecting conduit or return flue 13 is also disposed adjacent to the ceiling 1' and is preferably near one side of the drying room. It is provided with a series of branches or arms 22 extending through said ceiling and downward adjacent to the floor where the ports 23 are provided for collecting the cooled and vitiated air in the lower part of the room. Said return conduit is somewhat similar to the supply conduit respecting its adaptability to maintain a substantially uniform air pressure, sub-normal for suction, throughout its length. The pressure is negative rather than positive, as the return conduit is subject to the suction of the blower, tending to cause a vacuum whereby the air is driven into the conduit. For this purpose the size of the conduit is increased between the successive branching points 24 in the direction extending toward the air-treating means 3.

The ventilator 14 in conduit 13 near the attemperer 3 is provided with a vent flue 25 and an intake flue 26, said flues, together with the main flue at this point, being provided with valves or dampers 27, 28, and 29 respectively, adapted to cause discharge of the collected air outside of the building and replacement thereof by fresh air, or the air may be all returned to the air-treating means, or if desired, the said valves may be adjusted intermediately in such manner as to provide for partial exchange and partial re-treatment of the air, as will be readily understood by reference to the drawings. In this connection, see also my Patent No. 1,230,282. These valves may be thermostatically controlled as are the three similar valves shown in Fig. 4 and hereinafter described.

The distributing nozzles 20 are provided with dampers 30 adapted for adjustment for any desired capacity. Similarly, the collecting ports 23 are provided with adjustable dampers 30'.

In order to properly complete the drying process so as to insure a hard and durable flawless finish, means are provided in the finishing section or final stage for applying relatively cool moist air to the goods 11. For this purpose supply and return means 31 and 32 are furnished which are independent of the similar air-carrying means above described. To this end the supply conduit 31, which may be placed under the floor, is provided with two branches 33 and 34 dis-

130

closed crosswise of the drying room in spaced relation lengthwise of the room. Each of these branches diminishes in size step by step as at 35 between the outlet nozzles 36, toward the extremities remote from the source. The return conduit 32 is in the upper part of the drying room and is disposed transversely of the room. It is provided with a series of intake means 37. This 10 conduit also diminishes step by step as at 38 toward the end remote from the conditioning apparatus (not shown).

Means are provided in connection with the return conduit 32 for changing the air either 15 wholly or in part whenever desirable. Said means is in the form of a ventilator 39 with flues 40 and 41 and having valves 42, 43 and 44 arranged substantially in the same manner as described in connection with the corner 20 responding apparatus at the opposite end of the room. The attempering means for this supplemental or finishing step may to advantage be more or less combined with the main attemperer (Fig. 7), as will be understood, though above explained as a separate 25 means.

Automatic control of the temperature of the air at the several points indicated is effected by means of adjustable thermostats 30 operatively connected to the heating means through the medium of fluid pressure motors.

Such atmospherically responsive control means are shown in the fragmentary diagram of Fig. 8. The thermostatically controlled air pressure motors 45, 46, 47, 48, and 49, having valves connected therewith as understood in the art, regulate the passage of steam from the supply main 50 to the pre-heater 4, re heater 6, and the three boosters 18 respectively. The motor 51 is hygrometrically responsive to the degree of humidity of the air leaving the re heater 6 and serves to supply humidifying steam thereto if required in order to obtain the desired moisture.

The compressed air for operating the motors 45 et cetera, is supplied through the air main 52 leading to the air tank 53 adjacent to the control operator's panel 54.

The art of automatic control of the atmosphere by means which are responsive to changes in temperature or humidity or both is already well understood and fully explained in the published art. Hence, I will merely refer to certain United States patents showing atmospherically responsive means whereby any predetermined temperature and humidity may be maintained automatically by adjusting the apparatus accordingly. The Swan Patent, No. 1,277,771 shows interchangeable hygrometric and thermostatic elements adapted to effect either moisture or temperature control, an air 60 motor being used in connection therewith to

directly operate the steam valve, substantially as may be used in my drying room equipment. The Johnson Patent No. 542,733 shows a heat regulating apparatus, also using air motors to operate steam valves. 70

The drying room proper is preferably arranged, for the sake of efficiency and economy, with its ceiling 1' little more than high enough to clear the objects 11 to be treated, and it is for this reason that the 75 distributing and ventilating conduits are disposed in the space above the drying-room roof.

Referring to the air-treating equipment, it is to be understood that same may be of any 80 of the various well-known forms adapted to effect the desired treatment. The pre-heating member, the combined air-washer and humidifier, the reheating member, and the fan 55 and the motor 56 for operating 85 same may be variously designed to fit specific needs.

The return flue and ventilator valves 42, 43, and 44, see Fig. 4, may to advantage be operatively connected mechanically to one 90 another and to a thermostat 57, responsive to temperature changes in said flue, whereby control of the gradual replacement of used air by cool outside air may be effected automatically in a manner to maintain any 95 desired temperature at the point where the thermostat is located. The valves 27, 28, and 29 at ventilator 14 may be controlled in similar manner.

The operation of the drying room and associated apparatus is as follows: The goods to be treated, for instance, automobile bodies, having been sprayed or otherwise coated with varnish at the flow pans, and having stood sufficiently over the drip pans to eliminate all surplus varnish, are moved forward from the drip pans and distributed transversely in the cross space at the front end of the dryer room and distributed to the several runways or lines 10. The goods are carried preferably about 28" 105 from the floor, either on trucks or other suitable conveyers, not shown, as will be understood. The goods are permitted to remain a sufficient length of time in the first 110 stage to partly dry the varnish, whereupon they are moved forward successively through the remaining stages. This movement may be either slow and continuous or the goods may be advanced in batches periodically. 115

In the next to the last stage, the varnish drying is completed, whereupon the goods are delivered to the final or cooling stage, where the varnish is subjected to relatively 125 cool moist air, whereby it is acclimated for subsequent exposure to the outer air, without danger of developing fine cracks which result from sudden changes of temperature, and whereby it is made ready to be immedi- 130

ately handled without danger of being injured by contact with workmen's hands.

More specifically, in the first stage, where the temperature is moderate, the solvents

5 and thinners are evaporated from the varnish and the work as a whole is heated up without causing any "case hardening" or the formation of a surface film. The temperature in this stage may be held at about 100°
10 F. dry bulb and 86° wet bulb, corresponding to a relative humidity of 56% and with a moisture content of 11.07 grains per cubic foot.

In the second stage the oils in the varnish 15 are oxidized, so as to put the varnish in a sufficiently dry state to remove all trace of tackiness and to get the entire coat uniformly dry. This stage may be held at about 108° dry bulb and 88° wet bulb, corresponding to a relative humidity of 45% 20 and a moisture content of 11.12 grains per cubic foot.

In the third stage the varnish is sufficiently dried down and hardened so that the 25 object may be handled safely when cooled. Here the dry bulb may be maintained at 120° and the wet bulb at 90°, which corresponds to a relative humidity of 31% and moisture content of 10.73 grains per cubic foot.

In the last stage, which in this instance 30 is the fourth, the coating is subjected to an appropriately conditioned cooling atmosphere, where the varnish is acclimated for exposure to the outer air. Here the temperature may be 80° F. and the relative humidity 90%.

The operation of the air attempering and 35 distributing apparatus is substantially automatic when once adjusted and set into operation. The air of the drying room is circulated through the attempering means 3 and distributed in the manner above described, the rate of flow and the gradual renewal of the air through the ventilators being controlled by atmospherically responsive means adjusted manually from time to time to maintain the precise conditions desired. The automatic temperature control 45 means 4, 6, and 18, as well as the moisture controlling means, may also be adjusted from time to time as may be required.

In order to insure a substantially uniform 50 condition of the air adjacent to the ends and to enhance the efficiency of the device, movable closure means 58 and 59 are provided at the entrance and discharge ends of the drying room. Said means may be provided in various ways, as for instance 55 swinging doors or curtains may be used, as understood in the art.

As a result of this unified pluristage process, the product is uniform and dependable to a degree not practicable to obtain

commercially with devices heretofore 60 known, and the efficiency of the plant and labor elements of production are greatly increased.

Although but two specific embodiments 70 of this invention are herein shown and described, it is to be understood that some of the details of the methods and devices set forth may be altered or omitted without departing from the spirit of this invention as defined by the following claims. 75

I claim:

1. A system of the character described, comprising a common drying room adapted for the progressive movement therethrough of objects to be dried, means adapted to distribute a supply of air and to locally circulate same in successive parts of said room, and a plurality of air attempering means adapted and arranged in progressive order to effect nearly uniform graduated adjustment of atmospheric conditions along the path of said objects, so as to closely approach the best drying conditions for successive stages of the drying process. 80

2. A pluristage drying room provided 90 with an air distributing main extending therethrough, having attempering boosters positioned along its length and air outlets between said boosters.

3. A pluristage drying room provided 95 with an air distributing main having attempering boosters positioned along its length, atmospherically responsive means operatively associated with each of said boosters to automatically control their several effects in accordance with predetermined atmospheric conditions for the corresponding stages, and air outlets between said boosters. 100

4. A pluristage drying room having 105 means to provide atmospheric conditions of upwardly progressive temperature in the first stages and a diminution of temperature in the final stage.

5. A pluristage drying room having 110 means to provide atmospheric conditions of upwardly progressive temperature in the first stages and a diminution of temperature in the final stage, means being provided adapted and arranged to preheat the air 115 supply, means to wash the heated air, and means for heating different parts of the air going to the initial stages and the finishing stage respectively to different degrees responding substantially to a predetermined code. 120

6. A drying room having an air distributing main extending lengthwise thereof, said main having branches arranged with upwardly turned nozzles adjacent the 125 floor, in combination with a return main, motive means adapted to accomplish circulation of the air, and ventilating means

in the return main adapted to permit of partial renewal of the air to a greater or less extent during the operation of the device.

7. A drying room having successive stages merging one into another in which the atmospheric conditions are serially adapted to effect substantially the following results respectively on siccative coatings, first, drying out of the solvents and thinners, sec-

ond, oxidizing of the oils, and third, drying down and hardening the coating, the successive stages being adjusted for increasing temperature and decreasing relative humidity.

Signed at Chicago this nineteenth day of 15 January 1920.

CHARLES H. CURRIER.
